UNITED STATES PATENT OFFICE

136,051

DESIGN FOR A MAGAZINE RACK

Alfred V. Matifes, San Diego, Calif.

Application February 16, 1943, Serial No. 109,557

Term of patent 7 years

To all whom it may concern:

Be it known that I, Alfred V. Matifes, a citizen of the United States, residing at San Diego, in the county of San Diego and State of California, have invented a new, original, and ornamental Design for a Magazine Rack, of which the following is a specification, reference being had to the accompanying drawing, forming part thereof.

Figure 1 is a top plan view of a magazine rack, showing my new design; and

Figure 2 is a side elevational view thereof.

Figure 3 is a fragmentary perspective view showing the wheels and a portion of the frame of the magazine rack; and

Figure 4 is a perspective view of the container portion of the magazine rack.

I claim:

The ornamental design for a magazine rack, as shown and described.

ALFRED V. MATIFES.
